UNITED STATES PATENT OFFICE.

GEORGE B. McBEAN AND CHARLES W. BIRCHWOOD, OF CHICAGO, ILLINOIS, ASSIGNEES TO
MECHANICAL & ELECTRICAL MANUFACTURING COMPANY, OF CHICAGO, ILLINOIS, A
CORPORATION OF ILLINOIS.

REPAIR-TOOL.

No. 884,751.

Specification of Letters Patent.

Patented April 14, 1908.

Application filed December 2, 1907. Serial No. 404,797.

To all whom it may concern:

Be it known that we, GEORGE B. McBEAN, a citizen of the United States, and a resident of Chicago, Cook county, Illinois, and 5 CHARLES W. BIRCHWOOD, a subject of the King of Great Britain, and a resident of Chicago, Cook county, Illinois, have invented certain new and useful Improvements in Repair-Tools, of which the following is a specification.

This invention relates to repair tools particularly adapted for compressing the valve springs of gasoline motors and the like, to provide for relieving the pressure of the 15 springs on the valves in order that said valves may be conveniently removed.

As is well known, the valves of gasoline engines are almost always maintained normally closed by means of springs inserted 20 between rigid portions of the motor frame or valve casing and of the valve, usually cups, collars or the like, secured to the valve stems in proper position. When it is desired to remove the valves, it is necessary to relieve 25 the same from the pressure of the springs applied thereto.

The object of the present invention is to provide an improved tool for this purpose, which is of simple, strong and durable construction; which is efficient and convenient for the designed purpose and admits of a wide range of application; and which may be folded or nested into small compass to provide for conveniently carrying the same.

To effect the foregoing objects, a repair tool of our invention comprises the various features, combinations of features and details of construction hereinafter described and claimed.

In the accompanying drawings, in which our invention is fully illustrated, Figure 1 is a perspective view of our improved repair tool, showing the same in condition for use. Fig. 2 is a longitudinal sectional elevation 40 thereof taken substantially on the line 2-2 of Fig. 1, showing the fulcrum bar in folded or nested position. Fig. 3 is a fragmentary view, in perspective, showing a modified form of our improved tool, as regards the 45 fulcrum bar and fulcrum pin; and Fig. 4 is a partial sectional view through the valve chamber of a gasoline motor, showing the

valve in elevation, and a tool of our invention applied for compressing the valve spring which maintains said valve normally closed. 55

A tool of our invention comprises a lever, indicated as a whole, by A, formed of bars or members 1 and 2 rigidly connected to each other as by rivets 3 and 4 and spaced apart, as by washers 5 and 6 inserted over the rivets 60 3 and 4, thus forming a longitudinal slot or opening 7 in said lever A between the members 1 and 2 thereof. At one end the bars 1 and 2 are bent outwardly, forming a fork 8, pivoted between the sides of which are spring 65 engaging means, as shown a plate 9 provided with a slot 10 adapted to receive the stem of a valve to provide for inserting said plate 9 beneath a valve spring. As shown, said plate 9 is pivoted to the fork 8 by means of 70 lugs 11 on said plate. With this construction it is obvious that the plate 9 will be free to accommodate itself to varying positions of the valve spring, as the lever A is turned on its fulcrum. 75

Our improved tool also comprises a fulcrum bar 12 adapted to be inserted through the slot 7 in the lever A, formed in which are notches 13 adapted to engage a fulcrum pin 14 secured in the lever members 1 and 2 and 80 which extends across said slot 7. The fulcrum pin 14 is preferably located as close as practicable to the forked end 8 of the lever A and is preferably provided with a series of notches 13 to adapt the tool for use under 85 different conditions. The lower end of the fulcrum bar 12 is preferably pointed to insure a proper engagement of the end of said fulcrum bar with the part upon which it rests in use, usually a part of the motor frame, so as to prevent the same from slipping.

The fulcrum bar 12 is preferably made entirely separate and detached from the lever A, and is adapted to be inserted lengthwise 95 into the slot 7, as shown in Fig. 2, said slot being made of such width that the lever members 1 and 2 forming the sides of the slot 7 will frictionally engage the sides of said fulcrum bar 12 with sufficient force to prevent accidental disengagement thereof. Said slot 7 forms, in effect, a sheath or casing for 100 said fulcrum bar, thus providing for folding or nesting the different parts of the tool into

small compass to provide for conveniently carrying the same and, also, at all times insuring the presence of a fulcrum bar with the lever. As a further safeguard against accidental disengagement and possible loss of the fulcrum bar 12, we provide a notch 15 in the upper end thereof which is adapted to engage the fulcrum pin 14 when said fulcrum bar 12 is inserted into the slot 7.

10 Other means than those shown for removably securing the fulcrum bar 12 in the slot 7, will readily suggest themselves to mechanics of ordinary skill and we do not, therefore, desire to limit ourselves to the particular 15 means shown, which, however, on account of their simplicity and convenience, we now consider preferable for the purpose.

In Fig. 3 of the drawings, we have illustrated a modification of our improved tool, 20 said modification relating particularly to the means for engaging the fulcrum bar with the lever. In this modification, A¹ designates the lever, comprising members 1¹ and 2¹, 12¹ the fulcrum bar, and 14¹ the fulcrum pin. 25 The fulcrum pin 14¹, instead of being permanently secured in the lever A¹, is made separate therefrom, and is interchangeable in a series of holes 16 in the fulcrum bar 12¹. Said fulcrum pin 14¹ is longer than the thickness 30 of the fulcrum bar 12¹ and is designed to project at both sides thereof, so as to engage the under side of both members 1¹ and 2¹ of the lever A¹, notches 17 being preferably formed in the lower edges of said lever members 1¹ and 2¹ adapted to receive the projecting 35 ends of the fulcrum pin 14¹, whereby slipping of said lever on the fulcrum pin will be readily prevented. To fold or nest this form of our improved tool, it will obviously be necessary to remove the fulcrum pin 14¹. When 40 so removed, said fulcrum pin may be secured in a suitable hole or opening in the lever A¹ to prevent said fulcrum pin from being lost or misplaced. While this modification is less 45 convenient than the form of tool shown in Figs. 1 and 2 and is open to the further objection that it includes one more detached part or piece, it will obviously operate in substantially the same manner, and will be 50 equally effective for accomplishing the end designed, as the form of tool first described.

To illustrate the manner of using our improved tool, we have, in Fig. 4, shown the same as applied for its designed purpose of 55 compressing the valve spring of a gasoline motor.

The engine parts shown are of conventional form and will be readily understood by persons skilled in the art, without a detailed 60 description thereof, the valve B being maintained normally closed by means of a spring B¹ inserted between a shoulder b of the valve casing and a cup or plate b¹ secured to the valve stem B² by means of the usual key b² 65 inserted through a keyway formed in said

valve stem, the force of the valve spring B¹ being applied to the valve through the medium of said plate b¹ and key b².

When it is desired to remove the valve B, the plate 9 of our improved tool is inserted beneath the cup or plate b¹ on the valve stem, the fulcrum bar 12 is inserted through the slot 7 in the lever A and the fulcrum pin 14 engaged with one of the slots 13. By means of the lever A, the valve spring B¹ may now 75 be easily compressed to relieve the key b² from the pressure thereof and said key conveniently removed, whereupon the valve B, with its valve stem is free to be withdrawn through a suitable opening provided for the 80 purpose in the valve chamber, said opening being normally closed by means of a suitable plug B³.

We claim:

1. A repair tool comprising a lever provided with a longitudinal slot, a fulcrum bar and a fulcrum pin for operatively engaging said fulcrum bar with said lever, the slot in said lever being adapted to receive said fulcrum bar lengthwise, and means for removably 90 securing said bar in said slot.

2. A repair tool comprising a lever provided with a longitudinal slot, a fulcrum pin secured in said lever which extends across the slot therein, and a fulcrum bar adapted to be 95 inserted through said slot in said lever provided with a notch or notches adapted to engage said fulcrum pin, the slot in said lever being adapted to receive said fulcrum bar lengthwise, and means for removably securing 100 said bar in said slot.

3. A repair tool comprising a lever provided with a longitudinal slot, a fulcrum pin secured in said lever which extends across the slot therein, and a fulcrum bar adapted to be 105 inserted through the slot in said lever provided with a notch or notches adapted to engage said fulcrum pin, the slot in said lever being adapted to receive said fulcrum bar lengthwise, the relation being such that the 110 sides of said slot will frictionally engage the sides of said fulcrum bar when inserted therein.

4. A repair tool comprising a lever provided with a longitudinal slot, a fulcrum pin secured in said lever which extends across the slot therein, and a fulcrum bar adapted to be 115 inserted through the slot in said lever provided with a notch or notches adapted to engage said fulcrum pin, the slot in said lever being adapted to receive said fulcrum bar lengthwise, said fulcrum bar being provided with a notch in one end adapted to engage the fulcrum pin and the relation being such that the sides of said slot will frictionally engage the sides of said fulcrum bar when inserted 120 therein lengthwise.

5. A repair tool comprising a lever, said lever comprising rigidly connected, spaced 125 members forming a slot extending lengthwise 130

of said lever, a fulcrum pin secured in said lever which extends across the slot therein, a fulcrum bar adapted to be inserted through said slot and provided with a notch or notches 5 adapted to engage said fulcrum pin, the slot in said lever being adapted to receive said fulcrum bar lengthwise and means for removably securing said fulcrum bar in said slot.

6. A repair tool comprising a lever, said 10 lever comprising rigidly connected, spaced members forming a slot, extending lengthwise of said lever, a fulcrum pin secured in said lever which extends across the slot therein, and a fulcrum bar adapted to be inserted through said slot and provided with notches adapted to engage said fulcrum pin, the slot in said lever being adapted to receive 15 said fulcrum bar lengthwise and the relation being such that the sides of said slot will frictionally engage the sides of said fulcrum bar.

7. A repair tool comprising a lever, said 20 lever comprising rigidly connected, spaced members forming a slot extending lengthwise 25 of said lever, a fulcrum pin secured in said lever which extends across the slot therein,

and a fulcrum bar adapted to be inserted through said slot and provided with a notch or notches adapted to engage said fulcrum pin, the slot in said lever being adapted to receive 30 said fulcrum bar lengthwise, the relation being such that the sides of said slot will frictionally engage the sides of said fulcrum bar, and said fulcrum bar being provided at one end with a notch adapted to engage the 35 fulcrum pin.

8. A repair tool comprising a lever, a fork formed at one end thereof, and an integral plate adapted for engagement with a valve spring pivoted to said fork, said plate being 40 provided with a slot adapted to receive the the valve stem.

In testimony, that we claim the foregoing as our invention, we affix our signatures, in presence of two subscribing witnesses, this 45 21st day of November, A. D. 1907.
